(57) **CLAIM**

The ornamental design for a stand for computer enclosure, as shown and described.

DESCRIPTION

FIG. 1 is an isometric view of a stand for computer enclosure of our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a reduced scale isometric view thereof being mounted to a computer enclosure, wherein the computer enclosure is shown in broken lines for illustrative purposes only and forms no part of the claimed design.
